UNITED STATES PATENT OFFICE.

JOHN B. DAVIS, OF DAYTON, OHIO.

SELF-MEASURING OIL-PUMP.

No. 905,411.

Specification of Letters Patent.

Patented Dec. 1, 1908.

Application filed January 29, 1908. Serial No. 413,252.

To all whom it may concern:

Be it known that I, JOHN B. DAVIS, citizen of the United States, residing at Dayton, in the county of Montgomery and State of Ohio, have invented certain new and useful Improvements in Self-Measuring Oil-Pumps; and I do declare the following to be a full, clear, and exact description of the invention, such as will enable others skilled 5 in the art to which it appertains to make and use the same, reference being had to the accompanying drawings, and to the letters and figures of reference marked thereon, which form a part of this specification.

10 This invention relates to new and useful improvements in self-measuring pumps of the type used for dispensing oils, such for example, as gasolene, etc.

15 The object of the invention is to provide a single cylinder double-acting pump of the above type in which the valves are all located in exterior parts which are not integral parts of the pump proper, so that the said valves are rendered easy of access and the 20 construction is greatly simplified. It is desirable in these self-measuring pumps that they should be devoid of the least possible complication in order that the users thereof may be enabled to utilize them in the dispensing of oils without necessitating the 25 manufacturers of the pumps giving said pumps attention after they have been placed in the hands of the users.

30 Preceding a more detailed description of the invention, reference is made to the accompanying drawings, of which—

Figure 1, is a vertical mid-sectional elevation of the pump connected up and in an operative condition. In this view the upper 35 portion of the piston rod and the super-structure are removed and a portion of the middle part of the pump is broken out to facilitate illustration. Fig. 2, is an illustration of the pump in its entirety, the same 40 being an elevation thereof. Fig. 3, is an elevation of the pump looking from a position at right angles to Fig. 2. Fig. 4, is a view on the line *a a* of Fig. 2.

In a detail description of the invention, 45 similar reference characters indicate corresponding parts.

The pump has but one cylinder 1 which is inclosed at its upper end by a head 2 in the form of a special casting with internal 50 screw-threaded bosses 3 and a central aperture 4 through which the piston rod 5 passes,

there being a stuffing box 6 united to the head 2. The lower end of the cylinder 1 is inclosed by a base which is also of special construction and consists of the parts 7 and 8, 60 the latter being the stand which supports the pump. Between the base portions 7 and 8 there are oppositely-disposed internal screw-threaded openings 9 similar to the pipe openings 3 in the head. 65

Connected to the screw-threaded parts 9 of the base are special fittings in the form of pipes 10 and 11, the former being a straight pipe while the pipe 11 is in the form of an elbow. The pipe 10 is a comparatively 70 short fitting with which the suction or inlet pipe 12 is connected by a screw-threaded joint. The pipe fitting 10 has an interior portion 13 which provides a seat for a suction valve 14, the stem 15 of 75 which is guided in a detachable screw-cap 16 which is removable in order that access may be obtained to the valve. On the opposite side the elbow fitting 11 is likewise provided with an internal portion 14' which 80 provides a seat for a discharge or outlet valve 17 which discharges from the lower portion of the pump cylinder. This discharge valve 17 is provided with a cap 19 which forms a guide for the valve stem 18 85 and also enables ready access to the valve. The caps 16 and 19 screw into the upper portion of the pipe fittings 10 and 11 and their upper ends are provided with extensions which permit of the convenient use of a 90 wrench in removing and replacing said caps.

The suction pipe fitting 10 is provided with an internal screw-threaded T extension 20 which receives a nipple 21, the latter being connected to the lower end of a valve 95 casing 22 which stands parallel to the pump cylinder and is connected at its upper end to a pipe 23. The valve casing 22 provides a seat 24 for a check or suction valve 25, the stem 26 of which is guided in a central portion 100 of the casing 22.

27 is a screw cap in one side of the casing 22 providing access to said valve. The pipe 23 is connected to a short pipe or nipple 28 by means of a union 29 and the short pipe 105 28 is connected to the head of the cylinder by an elbow 30 which joins the apertured boss 3 on one side of the cylinder head 2. The union 29, together with the other parts just described, forms a rigid connection between the head of the cylinder and the base, 110 and the parts just described extending from

the T fitting 20 provide the inlet to the upper portion of the pump cylinder above the piston. The valve 14, which as before stated, is within the pipe 10, controls the 5 inlet to the lower portion of the cylinder. Connected to the discharge elbow 11 is a discharge pipe 31 for the lower end of the cylinder which receives the contents of that portion of the cylinder through the valve 17 10 in said elbow.

The discharge pipe 31 is joined at its upper end to a short pipe or nipple 32 by means of a union 29, and the nipple or short pipe 32 is united to a fitting 33 which has an 15 internal portion 34 that provides a seat for a discharge valve 35 for the upper end of the cylinder. The stem 37 of this discharge valve is guided in a screw-threaded cap 36 which is united to the upper side of the discharge fitting 33. It will thus be seen that 20 the fitting 33 provides two separate outlets, one for the lower end of the cylinder through the pipes 31 and 32, and one from the upper end of the cylinder through the 25 valve 35, said fitting 33 having an outlet or opening 38 which discharges into a pipe not shown. The lower end of the cylinder discharges a portion of the unit of measure while the upper portion of the cylinder dis- 30 charges the other portion of the unit of measure, but owing to a certain portion of the contents of the cylinder being displaced by the piston rod, it is essential that the lower portion of the cylinder or that portion 35 below the piston shall discharge the greater portion of the unit of measure, the excess being equal to the amount of oil displaced by the piston rod above the piston. The upper end of the piston rod is connected 40 to an operating rack 39 which has a foot 40 which is joined immediately to the upper end of said piston rod. The rack 39 is guided at its upper end in a head 41 which is supported on the upper end of the pump 45 by rods 42 which screw into apertured bosses on the top of the cylinder head 2.

The rack 39 and therewith the piston and piston rod, are reciprocated by means of a pinion 43 mounted upon a shaft 44 and 50 driven by a crank handle 45, the shaft 44 being mounted in the head 41. The piston 46 consists of upper middle and lower portions which inclose leathers 47 which are clamped between said piston portions by 55 nuts 48, the leathers being extended to fit against the walls of the cylinder and being constantly expanded to make the fit snug by means of coil springs 49 which encircle the piston and lie between the parts of the piston 60 proper and the leathers.

The head 2 of the cylinder is provided with stop marks 50 which indicate various quantities of oil to be dispensed from the cylinder, for example, pints, quarts, two 65 quarts, one gallon, two gallons, etc. Co-

operating with these stops is a lever 51 which is fixed to a rod 52, upon which rod there are several stops 53 which are rigidly united to said rod. These stops 53 are placed out of alignment with each other as shown in Fig. 4, and by moving the rod 52 by means of the handle 51 to any one of the marks 50, a particular stop 53 will be brought in a position to arrest the movement of the rack 39 by engaging the projected end 54 of the foot 40. It will thus be seen that the piston may be given variable movements to discharge quantities less than the full capacity of the pump.

It will be understood that the fundamental requirement of self-measuring pumps of this character, is that they shall measure accurately. In order that this may be accomplished in a single cylinder double-acting pump, it is necessary that each measure shall be taken from above and below the piston upon each up and down movement of the piston; that is to say, a portion of each measure shall be taken from one side of the piston and the other portion taken from the other side of the piston. This discharge of each measure would be equal from both sides of the piston were it not for the fact that the amount discharged from above the piston upon each upward movement of said piston, is less than half the measure, owing to an amount being displaced by the piston rod. This amount displaced by the piston rod is made up by the discharge below the piston, upon each downward movement of said piston, being in excess of one-half the quantity or measure, such excess being equal to the amount displaced by the piston rod above the piston. This capacity of the pump for discharging accurate measures despite the fact that the piston rod displaces an amount of oil above the piston at all times, is an important feature of my invention, which enables a single cylinder pump to discharge continuously accurate measures, during its operation. It will be seen that at all times the piston rod displaces a certain proportion of the oil above the piston, said portion displaced being equal to the length of the submerged portion of the piston rod multiplied by the cross-sectional area of said rod. Assuming for example, that it is desired to discharge from the pump a half gallon measure, the piston, in its upward movement will discharge a fraction less than one quart, owing to the displacement of oil by the piston rod. In the downward movement of the piston, it will discharge a fraction more than a quart, owing to no displacement of oil below the piston due to the piston rod, and thus the measure so taken from above and below the piston is an accurate quantity, for example, a half gallon. The upward stroke of the pump, in obtaining any measure-

ments, for example, pints, quarts, half gallons, gallons, etc., is regulated by the adjustable stops 53, by means of which the combined up and down strokes of the piston 5 will produce the desired accurate measure.

I claim:

In a single cylinder double-acting measuring pump, a pump cylinder, a piston and piston rod therein, an inlet and an outlet valve at each end of said cylinder, means 10 which enable said valves to communicate with the cylinder and whereby said cylinder is enabled to take in and discharge from above and below the piston, a pipe provid-

ing a common outlet for the outlet valves at 15 both ends of the cylinder, and means for regulating the stroke of the piston whereby the amount of oil discharged from below the piston compensates for the shortage in quantity discharged from above the piston 20 due to the displacement of oil by the piston rod upon the upward stroke of the piston.

In testimony whereof I affix my signature, in presence of two witnesses.

JOHN B. DAVIS.
